ABSTRACT OF THE DISCLOSURE

Cationic compounds of the 4,4' - bis - (s - triazinylamino) - stilbene - 2,2' - disulfonic acid series are useful as optical brighteners for fibrous materials, especially cellulose materials. These brighteners are compatible with cationic auxiliaries and operative when working at low pH values and thus capable of application together with cation-active laundry refining agents or crease-resistant finishing agents. They are, furthermore, useful for brightening paper pulps or paper coatings.

Derivatives of 4,4' - bis - (s - triazinylamino) - stilbene - 2,2'-disulfonic acid are already known in great number. As optical brighteners they have an outstanding economical importance. Of the water-soluble derivatives of this category of compounds only such products have been described hitherto in which the active brightener molecule is present as an anion (Type A):

In this formula, Y and Z represent neutral or negatively charged substituents, and M represents a cation. It may be assumed that the soluble alkali metal salts and equally the salts of the 4,4' - bis - (s - triazinylamino) - stilbene - 2,2'-disulfonic acid with amines dissociate in aqueous solution to a large extent into their ions, and that also the free disulfonic acids are dissociated, at least partially, into hydrogen ions and brightener anions, provided they are soluble in water. Also on the substrate ionic relation indicated in formula "A" is maintained. This is equally true for substrates such as cellulose fibers on which these brighteners are absorbed substantively, and for substrates with basic groups, such as polyamide and protein fibers on which the brightening anion is bound mainly in heteropolar manner on cationic centres.

From this type of anionic brighteners there may be distinguished such water-soluble derivatives of the 4,4' - bis - (s - triazinylamino) - stilbene - 2,2' - disulfonic acid in which the active brightener molecule is present as a cation (type B),

2

In this formula, Y₁ and Z₁ represent electro-neutral bridge members and X represents an anion.

The present invention relates to compounds of the type "B" and to a process for their preparation, and it demonstrates the clear advantages on some fields of application of these cationic derivatives over the above-mentioned anionic brighteners.

Now, we have found that compounds of the general Formula I

wherein A and A' which may be the same or represent hydrocarbon radicals containing 2 to 8 carbon atoms and which may be substituted by non chromophoric radicals, R¹ and R² which may be the same or different represent hydrogen or lower alkyl groups containing 1 to 5 carbon atoms, R³, R⁴, R⁵ and R⁶ which may be the same or different, represent lower alkyl groups containing 1 to 5 carbon atoms, a cycloalkyl group, preferably a cyclohexyl group, an aralkyl group, preferably a benzyl group, or an aryl group, preferably a phenyl group, and wherein each R³ and R⁴ as well as R⁵ and R⁶ may form, together with the nitrogen atom, a hydrogenated heterocyclic ring and R⁷ and R⁸ which may be the same or different, represent hydrogen, a lower alkyl group containing 1 to 5 carbon atoms or a benzyl group, and X represents a colorless anion, can be prepared by a process wherein the condensation product obtained in known manner from 1 mol of 4,4' - diamino - stilbene - 2,2' - disulfonic acid and 2 mols of cyanuric acid chloride is reacted at temperatures of about 20 to 40° C. with 2 mols of a diamine of the general Formula II

wherein A, R¹, R³, and R⁴ have the meanings indicated above, the reaction product obtained is further condensed at temperatures of from about 40 to about 100° C., preferably at 40° to about 80° C. with at least 2, preferably with 4 mols, of a diamine of the Formula III

wherein A', R², R⁵ and R⁶ have the meanings given above, the reaction product obtained is separated with 2 mols of the compound

R⁷X

wherein R^7 has the meaning given above and X represents a radical that may be split off as anion, in the form of an inner salt of the general Formula IV

wherein R^1 , R^2 , R^3 , R^4 , R^5 , R^6 , R^7 , A and A' have the meanings given above, and the compounds of the Formula IV are reacted with at least 2 mols of a compound of the formula

wherein R^8 has the meaning given above and X represents a radical that may be split off as anion.

The sodium salt of the 4,4'-bis-(2'',4''-dichloro-s-triazinylamino-(6''))-stilbene-2,2'-disulfonic acid obtained from 1 mol of 4,4'-diamino-stilbene-2,2'-disulfonic acid and 2 mols of cyanuric acid chloride is combined, if the diamines II and III are identical, with at least 4 mols, preferably with 6 mols, of this diamine. By heating to a temperature of about 40° C. for about 4 hours, in each of the two s-triazine rings first 1 chlorine atom and by subsequent heating to a temperature of about 100° C., preferably to about 80° C., the second chlorine atom is replaced by the radical of this diamine.

Working up may be effected as follows: the condensation products are first dissolved by addition of water and concentrated sodium hydroxide solution, the solution is clarified by addition of charcoal and the sodium salts of the Formula IVa

wherein R^1 , R^2 , R^3 , R^4 , R^5 , R^6 , A and A' have the meanings given above, are separated by addition of sodium chloride. From the strongly alkaline aqueous solution of the sodium salts the difficultly soluble inner salts IV (R^7 =hydrogen) can be separated by addition of acid up to a pH-value of 9 to 10. These salts can be easily identified by an analytic or titrimetric methods.

The inner salts IV wherein R^7 represents a lower alkyl group can also be precipitated from the strongly alkaline aqueous or aqueous-alcoholic solution of the sodium salts IVa by addition of 2 equivalents of an alkylating agent such as, for example, dimethyl sulfate. These salts too can be easily determined analytically.

Moreover, the following method of operation may be used: the aqueous solution of the sodium salts IVa is combined with such a quantity of acid that the internal salts of the Formula IV (R^7 =hydrogen) which have precipitated intermediately are dissolved again. In this case, clarification may be effected in an acid medium and the internal salt of the general Formula IV (R^7 =hydrogen) can be precipitated again by addition of sodium carbonate up to a pH-value of 9 to 10.

As diamines of the Formulae II and III there may preferably be used:

N,N-diethyl-1,2-diaminoethane,
N,N-di-n-propyl-1,2-diaminoethane,
N,N-di-n-butyl-1,2-diaminoethane,
N,N-di-n-pentyl-1,2-diaminoethane,
N,N-diethyl-N'-methyl-1,2-diaminoethane,
N,N,N'-triethyl-1,2-diaminoethane,
N,N-di-n-butyl-N'-ethyl-1,2-diaminoethane,
1-diethylamino-2-amino-n-propane,

- N-methyl-N-ethyl-1,3-diamino-n-propane,
N,N-diethyl-1,3-diaminopropane,
N-methyl-N-n-propyl-1,3-diamino-n-propane,
N,N-di-n-propyl-1,3-diamino-n-propane,
5 N-ethyl-N-n-butyl-1,3-diamino-n-propane,
N,N-di-n-butyl-1,3-diamino-n-propane,
N,N-di-n-pentyl-1,3-diamino-n-propane,
N,N-diethyl-N'-methyl-1,3-diamino-n-propane,
N,N,N'-triethyl-1,3-diamino-n-propane,
10 N,N-diethyl-N'-n-propyl-1,3-diamino-n-propane,
N,N-diethyl-N'-n-butyl-1,3-diamino-n-propane,
N,N-di-n-butyl-N'-ethyl-1,3-diamino-n-propane,
N-methyl-N-cyclohexyl-1,3-diamino-n-propane,
N-ethyl-N-benzyl-1,3-diamino-n-propane,
N-ethyl-N-phenyl-1,3-diamino-n-propane,
γ-piperidino-n-propylamine,
γ-morpholino-n-propylamine,
N,N-diethyl-1,4-diamino-n-butane,
N,N-di-n-propyl-1,4-diamino-n-butane,
20 N,N-di-n-butyl-1,4-diamino-n-butane,
N,N-diethyl-N'-methyl-1,4-diamino-n-butane,
N,N,N'-triethyl-1,4-diamino-n-butane,
N,N-di-n-butyl-N'-ethyl-1,4-diamino-n-butane;
1-diethylamino-4-amino-n-pentane,
25 1-di-n-butylamino-4-amino-cyclohexane,
1-di-n-butylamino-4-amino-n-pentane,
1-diethylamino-4-methylamino-n-pentane,
1-diethylamino-4-ethylamino-n-pentane,
1-di-n-butylamino-4-ethylamino-n-pentane,
30 1-diethylamino-4-amino-cyclohexane,
1-di-n-propylamino-4-amino-cyclohexane,
1-di-n-butylamino-4-amino-cyclohexane,
1-diethylamino-3-amino-cyclohexane,
1-di-n-propylamino-3-amino-cyclohexane,
35 1-di-n-butylamino-3-amino-cyclohexane,
1-diethylamino-2-amino-cyclohexane,
1-di-n-propylamino-2-amino-cyclohexane,
1-di-n-butylamino-2-amino-cyclohexane,
(4-amino-benzyl)-diethylamine,
40 β-(p-aminophenyl)-ethyl-diethylamine,
β-(p-aminophenyl)-ethyl-di-n-propylamine,
1-aminomethyl-4-dimethylaminomethyl-benzene,
1-aminomethyl-4-dimethylaminomethyl-cyclohexane;
2-amino-dimethylaniline,
3-amino-dimethylaniline,
45 3-amino-diethylaniline,
4-amino-diethylaniline,
2-amino-4-dimethylamino-toluene,
4-amino-2-dimethylamino-toluene,
50 4-amino-2-diethylamino-toluene,
6-chloro-3-amino-dimethylaniline,
2-chloro-4-amino-dimethylaniline,
6-bromo-3-amino-dimethylaniline.
- 55 The three last-mentioned substances are starting products for the preparation of compounds of the Formula I, wherein A or A' are substituted by non-chromophoric groups, i.e. by halogen atoms. Other non-chromophoric groups that may be used are cyano groups, lower alkoxy groups and lower carboxylic acid-alkyl ester groups.
- From the internal salts IV the compounds I of the present invention wherein R^7 and R^8 represent hydrogen are obtained by stirring the internal salts IV in water and dissolving them by addition of 2 equivalents of acid. It is advantageous, in order to obtain completely clear and stable solutions, to increase the amount of acid slightly and to adjust to a pH-value of about 5. As acids, strong inorganic acids, such as hydrochloric acid or sulfuric acid, may be used; organic acids, however, such as formic acid, acetic acid, propionic acid or oxalic acid, are also suitable. The compounds of the Formula I may be obtained in solid form by evaporation of their aqueous solutions under mild conditions. In practice, however, concentrated brightener solutions are preferred to powders since they are easier to handle. Therefore, it is advantageous to dispense

with the evaporation. In the following examples, the content of the solutions of the compounds I is mostly referred to the internal salts IV.

The compounds I of the present invention, wherein R⁷ and R⁸ represent a lower alkyl group or an aralkyl group, are prepared from the internal salts IV, wherein R⁷ represents hydrogen, by stirring the salts IV in water with 2 equivalents of sodium hydroxide solution and treating them with at least 4 to about 8 equivalents of an alkylating agent. A (greater) excess of alkylating agent might be used, but is in general of no advantage. As alkylating agents, there may be used the esters of sulfuric acid, such as dimethyl sulfate or diethylsulfate, or the esters of aromatic sulfonic acid, such as the p-toluenesulfonic acid-methyl ester. Alkyl or aralkyl halides, such as methyl chloride, methyl bromide, ethyl bromide, butyl bromide, benzyl chloride and benzyl bromide may also be used as alkylating agents.

Most of the compounds tested here are already peralkylated at temperatures of up to 50° C. and are dissolved without difficulty. In order to destroy the excess of alkylating agent used it is, however, advantageous to heat the solutions to about 60° C. and keep the solution in the alkaline pH range by adding dropwise sodium hydroxide solution, until no further change of the pH-value occurs. The concentrated solutions of the compound I obtained are used directly for brightening purposes after neutralisation and adjustment to a definite percent content (in general referred to the internal salts IV).

Some compounds of the general Formula I are relatively difficultly soluble in the presence of salts and precipitate from the alkylating solution. Their isolation is carried out in the usual manner by suction-filtering and washing with a solution of sodium chloride. If desired or required, a reprecipitation from water may be effected.

If the preparation of the compounds I of the present invention is started from the internal salts IV wherein R⁷ represents a lower alkyl group, it is sufficient to react these salts in aqueous suspension with at least 2 equivalents of an alkylating agent, for example dimethyl sulfate. The termination of the peralkylation is reached when from the solutions formed of the compounds I no difficultly soluble internal salts are separated when sodium carbonate is added at a pH-value of 9.

The preparation of the compounds I of the present invention in the manner last-mentioned is advantageous if highly concentrated salt-free brightening solutions are to be obtained.

Concentrated aqueous solutions of the products I of the present invention may also be obtained by addition of 2 equivalents of an inorganic and/or an organic acid to the internal salts IV wherein R⁷ represents a lower alkyl group.

Furthermore, we have found that the compounds of the general Formula I of the present invention are especially suited as optical brighteners for fibrous material, in particular for cellulose materials and in an especially advantageous manner for the brightening of paper. For this purpose, the compounds of the present invention which are either in liquid form or dissolved in water, are added to the paper pulp in the hollander, optionally before the addition of other auxiliary agents such as, for example, rosin size, aluminium sulfate etc., and by mixing thoroughly the pulp in order to disperse the brightener homogeneously, before forming the sheets in generally known manner on a wire.

These compounds are absorbed quantitatively and are retained in the paper sheet. The water flowing off from the wire is free from brightener, i.e. the process can be carried out without loss of brightener and pollution of the waste water.

The compounds of the present invention are clearly superior, in their brightening effect, both in non-sized as in sized and loaded papers, to the anionic brighteners of the type A hitherto used.

The cationic brighteners of the present invention show an equally very good brightening effect when used in coating mixtures for paper.

Furthermore, we have found that the compounds of the general Formula I of the present invention show a particularly good brightening effect when used together with cationic softening agents for fabrics and knit fabrics of cellulose fibers and fibers of regenerated cellulose. These laundry refining agents generally consist of fatty acid ammonium compounds, for example distearyl-dimethyl-ammonium chloride, and are used in laundry in the last rinsing operation in order to obtain soft and downy linen. By this treatment, however, the linen turns yellow to a certain degree. By addition of the compounds of the present invention, this yellowing can be avoided to a large extent.

The usual anionic optical brighteners (of type A) are incompatible with cationic softening agents and are blocked in their action to a large extent.

The products of the present invention show, when applied onto cellulose fibers, very good brightening effects, especially when used in a strongly acid medium, for example at a pH-value of 1 to 2. Thus, the new cationic brighteners may be used successfully together with auxiliary agents for the crease-proofing of cellulose fibers, for example with reactance resins, such as dimethylol-ethylene-urea, dimethylol-propylene-urea, dimethylol-monoalkyl-carbamate and others. Particularly high degrees of whiteness are obtained if the condensation of the synthetic resins is effected at a pH-value of 1 to 2, as it is usual in moist or wet cross-linking.

The following examples illustrate the present invention but they are not intended to limit it thereto. The parts by weight and parts by volume are in the same ratio as the kilogram to the liter.

EXAMPLE 1

A solution of 36.7 parts by weight of cyanuric acid chloride in 200 parts by volume of acetone was allowed to run into 700 parts by volume of ice water. To this suspension, a solution of 38.1 parts by weight of 4,4'-diamino-stilbene-2,2'-disulfonic acid (96.8% strength) in 400 parts by volume of water and 100 parts by volume of 2 N-sodium hydroxide solution was added dropwise, at a temperature in the range of from 0 to 5° C., and by simultaneous addition of about 90 parts by volume of 2 N-sodium carbonate solution, the pH-value was maintained at 2.5-3.5. When, by indirect diazotization no more diamino-stilbene-disulfonic acid could be detected, the reaction mixture was adjusted to a pH-value of 7 by means of 2 N-sodium carbonate solution.

70 parts by weight of β-diethyl-amino-ethylamine were added to the suspension of the sodium salt of 4,4'-bis-(2'',4''-dichloro-s-triazinylamino-(6''))-stilbene-2,2'-disulfonic acid thus prepared, the mixture was heated slowly to 40° C. and this temperature was maintained, while stirring, for 4 hours. The reaction mixture was then heated to 90-95° C., while acetone was distilled off, and boiled for 5 hours under reflux. The mixture was then diluted with 1000 parts by volume of water, the reaction product that had precipitated was dissolved at 60-70° C. by addition of about 45 parts by volume of a 33% sodium hydroxide solution, then clarified after addition of 10 parts by weight of charcoal and the clear filtrate was mixed with 520 parts by weight of sodium chloride. The sodium salt of the 4,4'-bis-(2'',4''-(β-diethylamino-ethylamino-s-triazinylamino-(6''))-stilbene-2,2'-disulfonic acid that had precipitated was filtered off with suction after cooling and washed with a 20% sodium chloride solution.

The sodium salt was dissolved in 1500 parts by volume of water at a temperature of from 50 to 55° C. and the pH-value of the strongly alkaline solution was adjusted to pH 10 by means of concentrated hydrochloric acid. The internal salt (1) (Table 1) that had precipitated crystallized upon further stirring at 15° C. The salt was separated by suction-filtration, washed with water until it

was free from chlorine ions and dried in vacuo at 60° C. 87 parts by weight of the compound (1) were obtained, corresponding to a yield of 88.5% of the theory.

60 parts by weight of the internal salt (1) were introduced into 150 parts by volume of water and dissolved, while stirring, by adding dropwise about 11 parts by volume of concentrated hydrochloric acid, at a pH of 3-4. The mixture was diluted with water to 300 parts by weight whereby a clear solution of the compound (34) (Table 2) was obtained (20% solution, referred to the internal salt).

49.25 parts by weight of the internal salt (1) were introduced into 100 parts by volume of water and mixed with 50 parts by volume of 2 N-sodium hydroxide solution. To the stirred mixture 25.5 parts by weight of dimethyl sulfate were added dropwise and the temperature was maintained at 35-50° C. by cooling. Stirring was continued for 2 hours at room temperature. In order to destroy any present dimethyl sulfate, the solution was subsequently heated to 60° C. while keeping the pH-value at 8 to 9 by dropwise addition to about 6 parts by volume of 2 N-sodium hydroxide solution. By addition of 2 N-sulfuric acid, the pH-value was then readjusted to 7 and the clear solution obtained of the compound (35) (Table 2) was filled up with water to the amount of 246.5 parts by weight (20% solution, referred to the internal salt).

9.85 parts by weight of the internal salt (1) in 50 parts by volume of water were mixed with 20 parts by volume of 2 N-sodium hydroxide solution and 8.8 parts by weight of p-toluenesulfonic acid-methylester and the mixture was heated to 50° C., while stirring. The mixture was kept for 4 hours at 50° C., then cooled to room temperature and the clear solution of the compound (36) (Table 2) that had formed was adjusted to a pH-value of 7 by means of concentrated hydrochloric acid. By diluting with water to 98.5 parts by weight, a 10% solution (referred to internal salt) was obtained.

EXAMPLE 2

78 parts by weight of N,N-diethyl-1,3-diaminopropane were added to the suspension of the sodium salt of 4,4'-bis-(2",4"-dichloro-s-triazinylamino-(6"))-stilbene - 2,2'-disulfonic acid, prepared according to Example 1, the whole was heated slowly to 40° C. and maintained, while stirring, for 4 hours at this temperature. The reaction mixture was then heated to 95° C., while acetone was distilling off, and boiled for 5 hours under reflux. The mixture was diluted with 2000 parts by volume of water, the reaction product that had precipitated was dissolved by addition of about 30 parts by volume of a 33% sodium hydroxide solution, clarified after addition of 20 parts by weight of kieselguhr, and the clear filtrate was combined with 230 parts by weight of sodium chloride. The sodium salt of the 4,4'-bis-(2",4"-(γ-diethylaminopropylamino) - s - triazinylamino-(6"))-stilbene-2,2'-disulfonic acid that had precipitated was stirred at room temperature, suction-filtered and washed with a 20% sodium chloride solution. The sodium salt was dissolved in 2000 parts by volume of water at room temperature and to the resulting solution there were added dropwise 50 parts by volume of concentrated hydrochloric acid until the precipitate formed was dissolved. The mixture was clarified by filtration and the filtrate was mixed with 100 parts by weight of sodium carbonate until it showed, with phenol-phthalein, a definitely alkaline reaction. The internal salt (2) (Table 1) which first precipitated in greasy form, was decanted several times with water, until no more chlorine ions could be detected. After drying in vacuo at 60° C., 62 parts by weight of compound (2) in solid form were obtained (60% of the theory).

60 parts by weight of the internal salt (2) were dissolved in 150 parts by volume of water by addition of 7.5 parts by volume of formic acid, at a pH-value of 5. The solution of the compound (37) (Table 2) was filled up with

water to the amount of 300 parts by weight (20% solution, referred to the internal salt).

52 parts by weight of the internal salt (2) in 150 parts by volume of water were mixed with 50 parts by volume of 2 N-sodium hydroxide solution and 25.5 parts by weight of dimethyl sulfate. The mixture was stirred for 1 hour at 35 or 40° C. and subsequently for several hours at room temperature. By addition of 2 parts by volume of 2 N-sodium hydroxide solution, the pH-value was maintained at 8. The solution of compound (38) (Table 2) was filled up with water to 250 parts by weight (20% solution, referred to the internal salt).

EXAMPLE 3

15 112 parts by weight of N,N-di-n-butyl-1,3-diaminopropane were added to the suspension of the sodium salt of 4,4'-bis-(2",4"-dichloro-s-triazinylamino-(6"))-stilbene-2,2'-disulfonic acid, prepared according to Example 1, the mixture was heated slowly to 40° C. and this temperature was maintained for 4 hours, while stirring. The reaction mixture was then heated to 95° C., while acetone was distilling off, and boiled for 5 hours under reflux. It was cooled to 15° C., the supernatant was decanted from the reaction product which had precipitated in semi-solid form, and the reaction product was mixed with 2000 parts by volume of water. By addition of about 60 parts by volume of concentrated hydrochloric acid, the reaction product was dissolved, the solution was clarified with 20 parts by weight of kieselguhr, and by addition of 100 parts by weight of sodium carbonate, the internal salt (3) (Table 1) was precipitated and suction-filtered. After washing to remove the chlorine ions and drying at 60° C. in vacuo, 119 parts by weight (94% of the theory) of compound (3) were obtained.

35 60 parts by weight of the internal salt (3) were dissolved in 150 parts by volume of water by addition of about 6 parts by volume of formic acid at a pH-value of 5-6. The solution of compound (39) (Table 2) was filled up with water to 300 parts by weight (20% solution, referred to the internal salt).

EXAMPLE 4

95 parts by weight of 1-diethylamino-4-amino-pentane were added to the suspension of the sodium salt of 4,4'-bis-(2",4"-dichloro-s-triazinylamino-(6"))-stilbene - 2,2'-disulfonic acid, prepared according to Example 1, the mixture was heated slowly to 40° C. and maintained at this temperature for 4 hours, while stirring. The reaction mixture was then heated to 95° C., while acetone was distilling off, and boiled for 5 hours under reflux. Then it was cooled to 20° C., the supernatant was decanted from the reaction product which had precipitated in resinous form, and the reaction product was dissolved by addition of 500 parts by volume of 2 N-hydrochloric acid and 1500 parts by volume of water. After having been stirred, the solution was clarified with 20 parts by weight of kieselguhr and the internal salt (4) (Table 1) was precipitated by addition of 100 parts by weight of sodium carbonate (until definite alkaline reaction with phenolphthalein). The compound which crystallized only difficulty was mixed several times with water in order to remove the chlorine ions, and dried at 60° C. in vacuo. 101 parts by weight of compound (4) corresponding to 88% of the theory, were obtained.

65 60 parts by weight of the internal salt (4) were dissolved in 150 parts by volume of water by addition of 4.5 parts by volume of formic acid at a pH of 5-6. The solution of compound (4) (Table 2) was filled up with water to 300 parts by weight (20% solution, referred to the internal salt).

EXAMPLE 5

A solution of 27.2 parts by weight of 3-amino-dimethyl-aniline in 50 parts by volume of acetone were added to the suspension of the sodium salt of 4,4'-bis-(2",4"-dichloro-s-triazinylamino-(6"))-stilbene-2,2'-disulfonic acid,

prepared according to Example 1. The mixture was stirred for 2 hours at room temperature, then heated to 40° C. and kept for 4 hours at this temperature. By adding dropwise 66 parts by volume of 2 N-sodium carbonate solution, the pH-value was maintained at 7. Then 46.5 parts by weight of β -diethylamino-ethylamine were added, the reaction mixture was heated to 95° C., while acetone was distilling off, and boiled for 5 hours under reflux. It was then cooled to room temperature, the supernatant was decanted from the reaction product which had precipitated in resinous form, and the reaction product was dissolved by addition of 500 parts by volume of 2 N-hydrochloric acid and 1000 parts by volume of water. After stirring, the solution was clarified with 10 parts by weight of kieselguhr, and by adding 100 parts by weight of sodium carbonate at pH 9-10 the internal salt (5) (Table 1) was precipitated. The crystalline product was suction-filtered, washed until it was free from chlorine ions and dried at 60° C. in vacuo. 98 parts by weight of compound (5) were obtained, corresponding to 96% of the theory.

30.7 parts by weight of the internal salt (5) in 100 parts by volume of water were mixed with 30 parts by volume of 2 N-sodium hydroxide solution and 22.7 parts by weight of dimethyl sulfate and the whole was stirred for 7 hours at room temperature. By adding dropwise 2 N-sodium hydroxide solution, the pH-value was maintained at 8 to 9. 34 parts by volume of 2 N-sodium hydroxide solution were necessary therefor. The supernatant was decanted from the reaction product which had precipitated in resinous form, and the reaction product was stirred with a 10% sodium chloride solution until crystallization occurred. The mixture was suction-filtered, washed with a 10% sodium chloride solution and dried at 60° C. in vacuo. 33 parts by weight of compound (41) (Table 2) were obtained. With regard to a content of 3.5% of sodium chloride, the yield corresponds to 92% of the theory.

EXAMPLE 6

A solution of 27.2 parts by weight of 3-amino-dimethyl-aniline in 50 parts by volume of acetone were added to the suspension of the sodium salt of 4,4'-bis-(2'',4''-dichloro-s-triazinylamino - (6'')) - stilbene-2,2'-disulfonic acid, prepared according to Example 1. The mixture was stirred for 2 hours at room temperature, then heated to 40° C. and kept for 4 hours at this temperature. By adding dropwise about 100 parts by volume of 2 N-sodium carbonate solution, the pH-value was constantly maintained at 7. Then 46.4 parts by weight of β -diethylaminoethylamine were added, the reaction mixture was heated to 75-80° C. while acetone was distilling off, and kept at this temperature for 1 hour. The reaction product, which crystallized during cooling, was suction-filtered, crushed to small pieces and washed with water on a suction filter until it was free from chlorine ions. The material obtained from the suction filter was introduced into 2000 parts by volume of water, 100 parts by volume of 2 N-sodium hydroxide solution were added and, after short stirring, a solution was obtained from which small impurities were removed by suction-filtering. 25.2 parts by weight of dimethyl sulfate were added dropwise in about 5 minutes to the clarified solution, the internal salt (7) (Table 1) precipitating thereupon. The suspension obtained was heated to 60° C. in order to convert the compound (7) into a coarse grained crystalline form, the suspension was kept for 15 minutes at this temperature, suction-filtered and the material obtained from the suction filter was washed with 3000 parts by volume of water. After drying at 60° C. in vacuo, 97 parts by weight of compound (7) were obtained (92% of the theory).

150 parts by weight of compound (7) were introduced into 500 parts by volume of water, combined with 35.8 parts by weight of dimethyl sulfate and stirred for 3 hours at room temperature. The solution obtained was then heated for 30 minutes to 70-80° C. and, after having been cooled, it was filled up with water to 925 parts

by weight. A 20% solution of compound (44) (Table 2) was obtained.

EXAMPLE 7

5 A solution of 32.8 parts by weight of 4-amino-diethyl-aniline in 50 parts by volume of acetone was added to the suspension of the sodium salt of 4,4'-bis-(2'',4''-dichloro-s-triazinylamino - (6'')) - stilbene-2,2'-disulfonic acid, prepared according to Example 1. The mixture was stirred for 2 hours at room temperature, then heated to 40° C. and kept at this temperature for 2 hours. By adding dropwise 35 parts by volume of 2 N-sodium carbonate, the pH was constantly maintained at 7. Then, 46.4 parts by weight of β -diethylamino-ethylamine were added, the reaction mixture was heated to 95° C. while acetone was distilled off, and boiled for 5 hours under reflux. After cooling and continuing the stirring for some time, the crystalline reaction product was suction-filtered and washed twice with water. The material obtained from the suction filter was introduced into 1000 parts by volume of water, dissolved by addition of 40 parts by volume of concentrated hydrochloric acid, and the solution obtained was clarified, after stirring, with 5 parts by weight of kieselguhr. The filtrate was mixed with 100 parts by weight of sodium carbonate, stirring was continued for 15 3 hours at room temperature, the crystalline internal salt (6) (Table 1) was suction-filtered, washed until it was free from chlorine ions and dried at 60° C. in vacuo. 105.5 parts by weight were obtained, corresponding to 98% of the theory.

20 32.4 parts by weight of the internal salt (6) were mixed in 100 parts by volume of water, with 30 parts by volume of 2 N-sodium hydroxide solution and 22.7 parts by volume of dimethyl sulfate and stirring was continued for 7 hours at room temperature. By adding dropwise 2 N-sodium hydroxide solution, the pH-value was maintained constantly at 8-9. 37.5 parts by volume of 2 N-sodium hydroxide solution were necessary therefor. The reaction product which had precipitated in crystalline form was suction-filtered and dissolved in 500 parts by volume of water at 70° C. This solution was clarified hot by addition of 5 parts by weight of charcoal and 5 parts by weight of kieselguhr, and mixed with 70 parts by weight of sodium chloride. The mixture was allowed to cool, while stirring, washed with a 10% sodium chloride solution and dried at 60° C. in vacuo. 29 parts by weight of compound (42) (Table 2) were obtained. With regard to the content of 5.5% of sodium chloride, the yield corresponds to 75.5% of the theory.

EXAMPLE 8

50 A solution of 32.8 parts by weight of 4-amino-diethyl-aniline in 50 parts by volume of acetone was added to the suspension of the sodium salt of 4,4'-bis-(2'',4''-dichloro-s-triazinylamino - (6'')) - stilbene - 2,2'-disulfonic acid, prepared according to Example 1. The mixture was stirred for 2 hours at room temperature, then heated to 40° C. and kept for 2 hours at this temperature. By dropwise adding about 50 parts by volume of 2 N-sodium carbonate solution, the pH-value was constantly maintained at 7. Then 46.4 parts by weight of β -diethylamino-ethylamine were added, the reaction mixture was heated to 75-80° C. while acetone was distilling off, and maintained at this temperature for 1 hour. The reaction product which crystallized upon cooling, was suction-filtered, crushed to small pieces and washed on a suction filter until it was free from chlorine ions. The material obtained from the suction filter was introduced into 500 parts by volume of ethanol and 1500 parts by volume of water, 100 parts by volume of 2 N-sodium hydroxide solution were added, and, after short stirring, a clear solution was obtained. 32.2 parts by weight of dimethyl sulfate were added dropwise to this solution in about 5 minutes, whereupon the internal salt (8) (Table 1) precipitated at first in greasy form. When stirred at room temperature, the salt became solid. It could be suction-filtered and washed with water after having been crushed to small pieces. After

11

drying at 60° C. in vacuo, 103 parts by weight of compound (8) were obtained (93% of the theory).

110.8 parts by weight of compound (8) were introduced into 400 parts by volume of water, combined with 25.2 parts by weight of dimethyl sulfate and stirred for 3 hours at room temperature. The solution obtained was then heated for 30 minutes to 70-80° C. and after cooling, it was filled up with water to 680 parts by weight. A 20% solution of compound (45) (Table 2) was obtained.

EXAMPLE 9

A solution of 27.2 parts by weight of 4-amino-dimethyl-aniline in 50 parts by volume of acetone was added to the suspension of the sodium salt of 4,4'-bis-(2",4"-dichloro -s - triazinylamino-(6"))-stilbene-2,2'-disulfonic acid, prepared according to Example 1. The mixture was stirred for 2 hours at room temperature, then heated to 40° C. and kept at this temperature for 2 hours. By adding dropwise 2 N sodium-carbonate solution, the pH-value was maintained constantly at 7. The 46.6 parts by weight of β -diethylamino-ethylamine were added and the reaction mixture was heated to 70-80° C., while stirring and cooling under reflux for 2 hours. The reaction product which had precipitated in crystalline form, was suction-filtered after cooling to room temperature and washed. The moist material obtained from the suction filter was dissolved in 2000 parts by volume of water and 500 parts by volume of ethanol, with addition of 100 parts by volume of 2 N-sodium hydroxide solution, and the solution was clarified at 50° C. To the filtrate obtained, 25.2 parts by weight of dimethyl sulfate were added dropwise and the methylation product that had precipitated was suction-filtered. The methylation product was then washed with 2000 parts by volume of water and dried at 60° C. in vacuo. 92 parts by weight of compound (9) (Table 1) were obtained, corresponding to 87.5% of the theory.

199 parts by weight of compound (9) (31.7% strength, corresponding to 63 parts by weight of a 100% compound) were mixed by stirring for 2 hours at room temperature, in 150 parts by volume of water, with 15.15 parts by weight of dimethyl sulfate until a clear solution had formed. This solution was heated to 70-80° C. for

12

30 minutes and, after cooling, it was filled up to 302 parts by weight. A 20% solution of compound (46) (Table 2) was obtained.

EXAMPLE 10

By operating according to the method described in Example 9, using 27 parts by weight of 4-amino-dimethyl-aniline and 52 parts by weight of N,N-diethyl-1,3-diaminopropane, 91 parts by weight of compound (10) (Table 1) were obtained, corresponding to 84.5% of the theory.

117 parts by weight of the moist compound (10) (46.2%, strength corresponding to 54.1 parts by weight of a 100% compound) were mixed by stirring for 2 hours at room temperature in 125 parts by volume of water, with 12.6 parts by weight of dimethyl sulfate, until a clear solution was obtained. This solution was heated to 70-80° C. for 30 minutes and after cooling, it was filled up with water to 332 parts by weight. A 20% solution of compound (47) (Table 2) was obtained.

EXAMPLE 11

134 parts by weight of the moist compound (11) (Table 1) (17.75% strength, corresponding to 23.8 parts by weight of a 100% compound) were stirred with 5.1 parts by weight of benzyl chloride for 24 hours at room temperature. A highly viscous solution of compound (49) (Table 2) was obtained, containing, after filling up with water to 150 parts by weight, 20% of this brightening agent.

EXAMPLE 12

260 parts by weight of the moist compound (12) (Table 1) (16.6% strength, corresponding to 43.2 parts by weight of 100% compound), were stirred for 24 hours at room temperature, after addition of 200 parts by volume of water, with 11 parts by weight of benzyl chloride. After filling up with water to 533 parts by weight, a 10% viscous solution of compound (51) (Table 2) was obtained.

The following Table 1 indicates the internal salts of the Formula IV of the present invention, and Table 2 lists the cation-active compounds of the Formula I of the present invention.

EXAMPLE 13

100 parts of dry, bleached soft wood sulfite pulp ground in a 4% aqueous suspension, in a hollander, to a beating degree of 40° SR. Then, 0.25 percent by weight of compound (37), referred to absolutely dry fibers, which had been previously dissolved in water, were added and the suspension was stirred thoroughly for about 10 minutes in order to disperse the brightener homogeneously. Finally the suspension was diluted with water in known manner to 0.5-1.0% by weight of pulp consistency, and run on a paper wire. The paper sheet that formed passed through the usual drying devices (wet pressing, drying cylinder). The water running off from the wire was free from bright-

EXAMPLE 16

Laundry refining agents were prepared using the following components:

(A)	Parts
5 Dimethyl-distearyl-ammonium chloride -----	5
Isopropanol -----	1.25
Oleyl alcohol-oxyethylate (molar ratio of oleyl alcohol to ethylene oxide 1:12) -----	0.5
Water -----	93.25

(B) Same as (A) but with addition of 0.1 part (100% active substance) of the anion-active optical brightener having the constitution

ener, the brightener remaining quantitatively in the paper. A comparison with a paper prepared without brightener showed that, by the indicated addition of the compound (37), the whiteness degree was greatly increased.

EXAMPLE 14

100 parts of dry bleached soft wood sulfite pulp were adjusted, in a 4% aqueous suspension, in a hollander, to a beating degree of 40° SR. This suspension was combined with 15%, referred to the fiber weight, of china clay, mixed thoroughly, and then combined with 0.3%, referred to the fiber weight, of compound (41) which had been previously dissolved in water in a dilution of 1:100, and again thoroughly mixed. After further addition of 3% by weight, referred to the fiber weight, of resin size, the suspension was adjusted to a pH of 4.5 by means of aluminum sulfate and mixed until it was homogeneous. After subsequent dilution to 0.5-1.0% by weight of solid material the sheets were formed in usual manner on a wire. Finally, the paper was dried as described in Example 7. Herein too, the brightener remained quantitatively in the paper and the water from the wire was free from brightener. Compared to a non-brightened paper the degree of whiteness was greatly increased by addition of compound (41).

EXAMPLE 15

There was prepared in known manner a paper coating mass (casein coating mass) having the following composition:

	Parts by weight
Polyphosphate -----	4
White pigment (for example china clay) -----	400
Casein -----	50
Pigment binder -----	30
Water for adjusting the viscosity.	

After having mixed the components (solids in dispersed form) in the indicated order, 10 g. of a 20% solution of compound (37) were added per liter of coating mass and the coating mixture was adjusted with water, at 20° C., to a viscosity of about 1000 centipoises (Brookfield Viscosimeter, 20 r.p.m.).

The coating mass so prepared was applied by means of a coating blade on wood-free paper having a weight of 90 g./m.². The dry coating amounted to 20 g./m.² of paper. The paper was then dried and calendered in the usual manner.

The paper coated and calendered in this manner showed a considerably better whiteness as a paper coated without addition of the compound (37).

(C) Same as (A) but with addition of 0.1 part of compound (41) (100% active substance).

Bleached white cotton fabrics were washed in the usual manner with a commercial brightener-containing detergent, then rinsed warm and cold, the last rinsing bath containing 4% of softening agent referred to the weight of the dry fabrics.

The after-treatment with agent (A) had produced a distinct yellowing which could not be removed even by application of an anion-active brightener according to Example (B). Only when applying the compounds of the present invention Example (C), the yellowing could be largely suppressed.

In order to support the visual evaluation the remission values of the test fabrics were measured in a "Zeiss Elrepho" apparatus (at 460 m.μ, remission values R, referred to MgO=1000).

Result:	R
Fabric non-treated -----	974
Fabric washed -----	1066
Fabric washed and aftertreated with agent A --	1012
Fabric washed and aftertreated with agent B --	1024
Fabric washed and aftertreated with agent C --	1042

EXAMPLE 17

Bleached cotton fabric was impregnated with a solution containing

2 g./l. of compound (37) (Table 2), and 150 g./l. of dimethylol-methoxyethyl-carbamate and which had been adjusted with oxalic acid, to a pH of 1.3. The fabric was squeezed between rollers until 100% liquor pick-up. The fabric was then dried for 45 seconds at 100° C., whereafter the fabric had a residual moisture of 7%. The cotton fabric was then rolled up, wrapped in a foil and stored for 20 hours at room temperature. It was then rinsed with addition of sodium carbonate at 40° C., until the fabric showed a neutral reaction. The dried material showed an excellent degree of whiteness.

EXAMPLE 18

Bleached cotton was impregnated with a solution containing

3 g./l. of the compound (37) (Table 2) 200 g./l. of dimethylol-4,5-dihydroxyethylene-urea, and 100 ml./l. of concentrated hydrochloric acid.

The fabric was squeezed between rollers with a squeezing effect of 70%. The fabric was rolled up, wrapped in a foil and allowed to stand for 20 hours at room temperature and then rinsed in water at 40° C., with addi-

tion of sodium carbonate, until it showed neutral reaction. The fabric treated in this manner showed an excellent degree of whiteness.

We claim:

1. A compound of the formula

wherein A and A' each is an alkylene of 2 to 5 carbon atoms, hydroxy-alkylene of 2 to 5 carbon atoms, 1,4-dimethylene-cyclohexane, cyclohexylene, 1,4-dimethylene-benzene, 4-benzylene, 4-phenylene, phenylene, toluylene, chlorophenylene or bromophenylene, R₁ and R₂ each is hydrogen or lower alkyl, R₃, R₄, R₅ and R₆ each is lower alkyl, benzyl, phenyl or cycloalkyl of 5 to 8 carbon atoms, or R₃ and R₄ and/or R₅ and R₆ together with the nitrogen atom are a six-member saturated heterocyclic ring, R₇ and R₈ each is hydrogen, lower alkyl or benzyl, and X is a colorless anion of a strong mineral acid, formic acid, acetic acid, propionic acid or oxalic acid, a mono-methyl or mono-ethyl ester of sulfuric acid, or a mono-methyl or mono-ethyl ester of an aromatic sulfonic acid.

2. A compound according to claim 1 wherein A and A' each is an alkylene of 2 to 5 carbon atoms, phenylene, toluylene or chlorophenylene, R₁ and R₂ each is hydrogen, R₃, R₄, R₅ and R₆ each is lower alkyl or phenyl, or R₃ and R₄ and/or R₅ and R₆ together with the nitrogen atom is morpholino or piperidino, R₇ and R₈ each is hydrogen, methyl or benzyl, and X is chloride, methosulfate, toluene sulfonate or formate.

3. The compound of the formula

4. The compound of the formula

5. The compound of the formula

20 6. The compound of the formula

7. The compound of the formula

8. The compound of the formula

9. The compound of the formula

19. The compound of the formula
